ATTORNEY'S

UNITED STATES PATENT OFFICE.

FRANKLIN J. GUSTINE, OF NEW ORLEANS, LOUISIANA, ASSIGNOR OF ONE-HALF TO CHARLES CARROLL, OF SAME PLACE.

SPRING-OPERATED MECHANICAL TOY OR ANALOGOUS DEVICE.

SPECIFICATION forming part of Letters Patent No. 655,621, dated August 7, 1900.

Application filed November 20, 1899. Serial No. 737,684. (No model.)

To all whom it may concern:

Be it known that I, FRANKLIN J. GUSTINE, a citizen of the United States, residing at New Orleans, in the parish of Orleans and State of Louisiana, have invented certain new and useful Improvements in Spring-Operated Mechanical Toys or Analogous Devices; and I do hereby declare the following to be a full, clear, and exact description of the invention, 5 such as will enable others skilled in the art to which it appertains to make and use the same.

My invention relates to improvements in mechanical toys, and particularly to that class of mechanical toys known as "spinning-tops;" and it consists in a novel combination of two tops—the one provided with an impelling-spring and means for so locking the two together that when dropped upon a hard surface the upper top becomes separated from 15 the lower top, and the two are caused to spin independently.

My invention will be understood by reference to the accompanying drawings, wherein the same parts are indicated by the same figures throughout the several views.

Figure 1 represents a view in elevation of the two tops locked together. Fig. 2 is a sectional view of the upper or "passive" top, and Fig. 3 is a similar view of the lower or 20 "active" top.

The upper top consists of a hollow body or shell 1, or may be solid, if preferred, being hollow for the sake of cheapness and lightness, through which extends axially a rigid 25 straight cylindrical stem 3, the lower end of which stem projects beyond the bottom surface of the shell 1 and has a rounded point upon which the said body may spin after the manner of such tops. The lower projecting 30 end of the stem 3 is provided with a laterally-projecting lug or stud 4, as seen most clearly in Fig. 2. The upper end of the stem 3 may or may not project above the body of the top.

The lower top has a body or a hollow or shell-like form 2, similar in exterior appearance to the upper top. This lower top has, however, an axial stem 5, which is mounted loosely therein, having both a rotary movement and an axial movement with respect to the shell 45 2. Within the shell 2 is formed a hollow casing 9, containing a coiled spring 11, one end

of which spring—the inner end—is secured at 12 to the stem 5, and the other or outer end of which spring is secured at 13 to the casing 9, as seen in Fig. 3. The spring has 55 sufficient lateral stiffness to support the body of the top upon the stem in its spinning position, but allows of an axial movement limited by the upper and lower walls of the casing 9. The stem 5 is preferably hollow, or at 60 least is so at its upper end, at which end it is cut to form a cam-clutch member 6, arranged to coöperate with an oppositely-formed cam-clutch member 7, formed upon an inclosing cylindrical extension 8 upon the surrounding 65 portion of the upper part of the shell 2.

The lower end of the stem 3 of the upper top fits loosely within the upper end of the hollow stem 5 of the lower top, and the projecting stud 4 of the stem 3 is arranged to engage between the vertical faces of the clutch members 6 and 7, to lock the two tops against backward rotation with respect to each other after having been wound in opposite directions to the extent of the spring 11. 75

The operation in winding and locking together the two tops is as follows: The one top being held in one hand and the other top being held in the other hand, the lower end of the stem 3 of the upper or passive top 80 is inserted into the hollow upper end of the stem 5 of the lower or active top and the two tops are turned in opposite directions about their common axis. As the winding proceeds the stud 4 on the stem 3 will slide 85 upward over the cam-faces of the clutch 7 on the lower top-body, but will cause the rotation of the stem 5 by reason of its engagement with the vertical clutch-face on said stem. When wound to the limit of the spring 90 11, the stud 4 is caused to engage behind the vertical clutch-face of the clutch 7, thus locking the upper top, its stem, and the stem of the lower top against backward rotation under the influence of the spring 11 until disengaged. The tops are spun by being dropped 95 so that the bottom end or tip, which is rounded, of the stem 5 of the lower top strikes sharply upon the surface upon which the tops are to be spun, and this causes an 100 axial movement of the body 2 of the lower top with respect to the stem 5 thereof, said

movement being downward, and this disengages the cam 7 on the extension 8 of the top-body 2 from the stud 4 on the stem of the upper top. The tension upon the spring 11 thus being removed, the latter reacts upon both the body 2 of the lower top and its stem 5, causing a rapid rotation of both in opposite directions. The rotation of the stem 5 of the lower top gives a sudden impetus to the stem of the upper top through the stud 4 on its stem, causing the upper top to be thrown off bodily with a spinning motion, which causes it to float in the air for an instant and then settle down upon a convenient surface, where it will spin until the force thus imparted to it is expended. The action of the spring upon the stem of the lower top is exhausted in imparting this impetus to the upper top, so that when the upper top has been thrown off the lower top will continue to spin by reason of the impetus given the body thereof by the rebound of the spring, the two tops spinning in opposite directions.

I do not wish to limit myself to the precise details of construction herein shown and described, as these may very well be varied within reasonable limits without departing from the spirit of my invention.

Having thus described my invention, what I claim, and desire to secure by Letters Patent of the United States, is—

1. In a mechanical toy, the combination with a spinning-top having a hollow body and a hollow stem passing through said body, a coiled spring fixed at one end within said body to an integral portion thereof and fixed at its opposite end to and surrounding said hollow stem, the said hollow stem being allowed axial movement with respect to said body, one end of said stem having a spinning-point and the opposite end having a locking clutch member formed thereon, and the said body having cylindrical extension concentric with said stem and provided with a locking clutch member, the opposite of the clutch member on the said stem; of a second spinning-top having a rigid stem provided with a spinning-point at one end adapted to enter loosely the open end of the said hollow stem, and having near its spinning end a projection arranged to engage

said clutch members and to lock the body and stem of the first-named top together under tension upon said spring, the projection being arranged to become disengaged from the clutch member on the body of the first top by the axial movement of the hollow stem and the said tops receiving independent rotation by the reaction of said spring, substantially as described. 55

2. In a mechanical toy, the combination 60 with a spinning-top provided with a hollow stem, a coiled spring loosely connecting said body and stem and allowing axial movement of the stem with respect to the body; of a second top having an integral or rigidly-connected body and stem, the latter provided with a spinning-point; means whereby the two tops may be connected together and the body and stem of the first-named top locked against rotation, and means for causing the 65 disengagement of the two tops and their rotation in opposite directions upon the unlocking of the stem and body of the first-named top, substantially as described. 70

3. In a mechanical toy, and in combination, 75 two spinning-tops, the one containing the impelling mechanism for both, and the other provided with means for locking such impelling mechanism under tension, and for receiving an impetus therefrom when suddenly 80 released from such tension, substantially as described.

4. In a mechanical device, the combination with a body comprising two concentric rotary elements; a spring loosely connecting said 85 rotary elements; and means whereby said elements may be locked against rotation with respect to each other; of a body provided with means for locking said elements under tension, arranged to become disengaged and 90 to unlock said elements upon the axial movement of one of such elements, substantially as described.

In testimony whereof I affix my signature in presence of two witnesses.

FRANKLIN J. GUSTINE.
